UNITED STATES PATENT OFFICE

ROSARIO BELLO, OF TRENTON, NEW JERSEY

DETACHABLE RUBBER HEEL

Application filed October 17, 1928. Serial No. 313,121.

My invention relates to new and useful improvements in detachable rubber heels, and has for an object to provide a rubber heel that may be purchased with the little nails or studs already fitted within sockets in the rubber heels so that to apply the heels it is only necessary to lay the same in position on the leather heels and hit the surface of the heel a sufficient number of times to drive the little studs in the leather, and thus hold the heel in position.

When it is desired to replace the heel, the little studs may be removed from the new rubber heel, or it may be that the heel may be purchased without the little studs in place.

Still another object of the invention is to provide a rubber heel wherein there are provided a plurality of little sockets on the inner surface of the heel, while the tread is provided with a plurality of little rubber lugs to reinforce the heel directly behind the little sockets.

Still another object of the invention is to provide a slightly modified form wherein there are a plurality of little studs and sockets, the sockets having little projections or points on their rear face so that an ordinary rubber heel may quickly be converted into a detachable rubber heel and easily placed in position on a shoe.

Still another object of the invention is to provide an easily removable rubber heel, and at the same time so form the heel that when the heel is applied the little socket will receive a part of the force from the hammer and tend to make the sockets more tightly grip the studs than would otherwise be the case.

With these and other objects in view, the invention consists in certain new and novel arrangements and combination of parts, as will be hereinafter more fully described and pointed out in the claim.

Referring now to the drawings showing a preferred and a modified form of the invention,

Fig. 1 is a perspective of a shoe with a rubber heel about to be placed in position.

Fig. 2 is a tread surface of the heel.

Fig. 3 is a sectional view showing the rubber heel in position.

Fig. 4 is a view similar to Fig. 1 but showing a replacement, and

Fig. 5 is a sectional view of a slightly modified form.

Referring now to Figs. 1 to 4 inclusive, there is shown a shoe 1, having the sole 2, the ordinary leather heel 3 and a rubber heel 4 in which there is embedded a plurality of little socket members 5, these being preferably molded right within the rubber heel.

The tread surface of the heel is provided with a plurality of little rubber lugs 6 molded in place when the heel is made, and it will be noticed that these little lugs are directly over each of the little socket members 5.

I also employ a number of little studs 7 provided with little heads 8 adapted to snap within the sockets 5. The fit of the little socket and stud head is such, however, that by applying quite a little pull, the studs may be removed from the socket heads, or, of course, after the heel is in position, the sockets will be pulled away from the little stud heads.

To apply the heel, it is only necessary to place the little studs, that is, the heads of the studs, within the little sockets as shown in Fig. 1, or, possibly the studs may be within the sockets when the heels are purchased. In either event, after the little studs are in position as shown in Fig. 1, it is only necessary to lay the rubber heel in position, and pound each of the little rubber lugs 6 with a hammer to thus drive the little studs within the leather heel.

By providing these little rubber lugs on the tread surface, it makes a better tread or gripping surface for the heel and it also reinforces the heel directly over the little embedded sockets.

Another advantage, also, is that when these rubber lugs are pounded with the hammer, there will be a tendency to flatten out the little sockets to make them more tightly grip the heads of the lugs and will thus provide a tighter fit.

After the heel is worn to the point where it should be discarded, it is only necessary

to rip off the rubber heel, and the little studs 7 will remain in the leather heel as shown in Fig. 4. A new rubber heel may then be placed in position so that the little studs again fit within the respective sockets in the rubber heel.

By purchasing the heel with the studs therein or by placing the little studs in the sockets before the heel is applied, it is unnecessary to have to mark the leather heel where the studs would have to be placed to register with the sockets.

In the modified form shown in Fig. 5, there is shown the manner in which an ordinary rubber heel is converted into a detachable rubber heel, and in this instance the little sockets 10 are provided with little prongs on their rear surface and these may be driven around the inner surface of the heel at desired points. The little studs 11 may then be placed in the socket and the rubber heel again hit with a hammer to force the little studs in their proper respective positions.

After the rubber heel has been worn away, an ordinary rubber heel may have new sockets placed therein and placed in position, or the new heel as shown in the preferred form with the sockets embedded therein may be applied.

I am aware that it is old in the art to make replaceable or quickly detachable rubber heels, but in most instances it is hard to mark the position where the little lugs are to be placed and an ordinary person in endeavoring to position the lugs would find no little difficulty in correctly spacing them.

Having thus described my invention, what I claim as new and desire to secure by Letters Patent is:—

In combination with a shoe having a rubber heel member, means for securing the rubber heel member to the shoe consisting of a socket member having a prong adapted to be driven into the rubber heel member, said socket member when driven into the rubber heel member adapted to have associated therewith a stud having a pointed end in alignment with the point on the socket member and said stud when so associated being adapted to be attached to the shoe.

In testimony whereof I affix my signature.
ROSARIO BELLO.
